UNITED STATES PATENT OFFICE.

ADOLPH STORM, OF MINNEAPOLIS, MINNESOTA, ASSIGNOR TO STORM MANUFACTURING COMPANY, OF MINNEAPOLIS, MINNESOTA, A COPARTNERSHIP CONSISTING OF SAID STORM AND O. W. NELSON.

CYLINDER-FINISHING TOOL.

Application filed October 30, 1922. Serial No. 597,866.

To all whom it may concern:

Be it known that I, ADOLPH STORM, a citizen of the United States, residing at Minneapolis, in the county of Hennepin 5 and State of Minnesota, have invented certain new and useful Improvements in Cylinder-Finishing Tools; and I do hereby declare the following to be a full, clear, and exact description of the invention, such 10 as will enable others skilled in the art to which it appertains to make and use the same.

My invention provides an improved and 15 highly efficient cylinder-finishing tool, and, generally stated, the invention consists of the novel devices and combinations of devices hereinafter described and defined in the claims.

This improved tool, herein designated as 20 a cylinder-finishing tool, is adapted to be used to polish and finish the cylindrical surfaces of new or rebored engine cylinders. In fact, the tool is adapted for use to true up old cylinders without requiring rebor- 25 ing where but little metal needs to be removed!

The preferred form of the tool is illus- 30 trated in the accompanying drawings, wherein like characters indicate like parts throughout the several views.

Referring to the drawings:

Fig. 1 is a side elevation of the improved 35 tool;

Fig. 2 shows the tool chiefly in section 40 on the line 2—2 of Fig. 1, but with some parts in full and with the tool applied in a cylinder; and

Fig. 3 is a horizontal section taken on the line 3—3 of Fig. 2.

The cylinder casting is indicated by the 45 numeral 4. The finishing tool is adapted to be carried and rotated by any suitable means, but, as shown, is carried at the lower end of an upright rotary spindle 5. Said 50 tool comprises a head 6 into which a trun- nion on the lower end of the spindle 5 is shown as axially screwed. Said head 6 has a large axial cylindrical cavity 7 and, below said cavity, has a diametrical slot 8. At 55 its extreme lower end, extending trans- versely and centrally of the slot 8, the head 6 is provided with a transverse bridge 9. Pivoted on the bolts 10 applied to oppo- site sides of the head 6 are downwardly di-

verging gripper-carrying levers 11. Each 55 lever 11, as shown and preferably designed, comprises a pair of rigidly connected metal straps, the lower portions of which are spread to form forks 12. These forks 12 embrace the sides of hone or grinding stone 60 grippers 13 and, at their lower ends, are pivotally connected to the central portions thereof by nut-equipped bolts 14. These grippers 13 are preferably channel-shaped stamped metal structures, the sides of which 65 are adapted to be sprung together by clamping bolts 15 and thereby firmly clamped to the hones or grinding stones 16. As shown, the grippers 13 are pro- 70 vided with outstanding centrally located ears 17 that are connected by a light coiled spring 18, the function of which will pres- ently appear.

Working with threaded engagement 75 through the bridge 9 and extending ax- ially of the head 6 into the cavity 7 there- of is an anchor bolt 19, to the upper end of which a flange 20, as shown in the form of a washer, is rigidly secured by a clamp- 80 ing nut 21. A disk-like follower 22 is slid- ably mounted on the smooth portion of the bolt 19 and engages the short lug-like upper end projections 23 of the levers 11. A coiled spring 24 loosely surrounds the 85 bolt 19 and is compressed between the relatively fixed flange 20 and slidable or loose follower 22. This spring 24 is of such strength that it readily overcomes the relatively light tension of the spring 18 and, normally holds the levers 11 spread 90 as far as permitted by the engagement of the follower 22 with a shoulder 25 formed on the bolt 19 at the upper extremity of its threaded lower portion. The extreme lower threaded end of the bolt 19 is pref- 95 erably formed with a transverse slot 26 adapting it to be readily turned by a screw driver.

Operation.

Normally or when the tool is outside of 100 the cylinder, the main tension spring 24 will hold the follower 22 against the shoul- 105 der 25, thereby determining the normal spread of the outer grinding faces of the two hones 16, but it is obvious that the farther the bolt 19 is screwed down through the bridge 9, the wider will be the spread

of the two hones under the normal condition above just noted. In adjusting the tool for any particular cylinder, the bolt 19 should be set so that the follower 22 will 5 be slightly above the shoulder 25 when the hones are active against the inner surface of the cylinder. The spring 18 simply takes up slack and keeps the lugs 23 of the levers 11 lightly pressed against the follower 22, when not in use, but the tension of said spring 18 does not, in any case, interfere with the action of the spring 24, the function of which latter is to keep the hones pressed outward into engagement 10 with the cylinder under the proper grinding tension.

With the bolt 19 set in a certain position, it is evident that the spring 24 will have increasing tension as the hones are moved 20 closer together and, hence, that in the absence of a provision for adjustment, the hones would be forced against cylinders of different sizes, under different pressures. This is entirely avoided with the arrangement 25 described, for with the hones set into any particular cylinder, the bolt 19 may be adjusted axially so as to give exactly the desired pressure. It, of course, also follows that the spring 24 may be set under 30 any desired tension for any particular diameter of cylinder but may be constant in pressure for cylinders of different diameters.

This improved tool, by virtue of the construction 35 already described, has another and very highly important action which will now be fully considered.

It is evident that if one of the levers 11 be moved toward the axis of rotation while the other lever remains in a more divergent position, the said first moved lever will be subject to the entire tension from the spring 24. From this, it follows that the two levers will be subject to the same tension from the spring 24 when and only when the axis of the shaft 5 and head 6 is coincident with the axis of the cylinder into which the hones have been inserted. If, for instance, the said axis is closer to the right-hand than 45 to the left-hand side of the cylinder, then the spring 24 will exert a lateral thrust through the right-hand lever 11, which will tend to move either the cylinder toward the right or the shaft 5 and head 6 toward the left, until the axis of the tool is coincident with the axis of the cylinder, and when the cylinder is free to shift in respect to the head 6 or the said head 6 is free to shift in respect to the cylinder, the accurate alignment 55 of the tool with the cylinder will be automatically accomplished by the rotation of the tool within the cylinder.

The above self-centering action is highly important and, of course, would not be 60 present with a spring, for example, having

its basis of reaction directly against or between the two levers.

In actual practice, the efficiency of this tool has been thoroughly demonstrated. The hones or grinding stones may be of any 70 material which will put an extremely smooth finish on the interior of the cylinder. In some cases, they might even be coarse for rapidly removing the interior surface of the cylinder, but usually they will be of fine 75 grain for producing a fine finish.

The term "hone" is herein used in a broad and liberal sense to include any kind of abrasive finishing or cutting block or the like. In the most approved arrangement of 80 the tool, the head will be rotated while the cylinder being finished will be held against rotation, frictionally or otherwise, but it would be within the scope of the invention as herein claimed to hold the finishing tool 85 against rotation and to rotate the cylinder.

What I claim is:

1. A tool of the kind described comprising a rotary head, levers pivoted to said head, finishing hones pivotally carried by the extended ends of said levers, a spring tension device carried by said head and independently reacting against said levers and exerting a force thereon tending to spread said levers and finishing hones, said spring tension device being adjustable as an entirety, so as to vary the spread of said levers without changing the tension of said spring tension device. 90

2. The structure defined in claim 1 in further combination with means for adjusting the tension of said spring tension device independently of its adjustments as an entirety. 100

3. A tool of the kind described comprising a rotary head, levers pivoted thereto, finishing hones pivotally carried by the extended ends of said levers, a spring tension device reacting against said head and independently reacting against said levers and exerting a force thereon tending to spread said levers and finishing hones, the said spring tension device having a stop normally limiting the action on said levers, and means for adjusting said stop and the base of reaction of said spring tension device in respect to said levers. 105

4. A device of the kind described comprising a rotary head, a plurality of levers pivoted to said head at their upper ends for swinging movements in planes radiating from the axis of said head, said levers at their pivoted upper ends having inwardly offset bearing lugs, a spring-pressed follower seated in said head and independently operating on the bearing lugs of said levers and exerting force tending to move said levers radially outward, and finishing tools pivoted to the free ends of said levers. 110

5. A device of the kind described com- 120

prising a rotary head having an axial cavity and below said cavity having diametrically opposite slots and an intermediate bridge, an axial bolt working with screw-threaded engagement through said bridge and extending into the cavity of said head, a tension spring surrounding said bolt, a base of reaction for said spring secured to the upper end of said bolt, a follower slidable on said bolt and subject to said spring and having a limited downward movement on said bolt, a pair of levers pivoted to said head within

the diametrically opposite slots thereof and having upper ends independently engageable with said spring-pressed follower, grippers 15 intermediately pivoted to the lower ends of said levers, and hones held by said grippers.

6. The structure defined in claim 5 in combination with a retracting spring connecting said grippers and exerting a 20 force thereon in opposition to but materially less than the said tension spring.

In testimony whereof I affix my signature.
ADOLPH STORM.
